UNITED STATES PATENT OFFICE.

JAMES HYTER REICHART, OF LA FAYETTE, INDIANA.

ILLUMINATED FOUNTAIN.

1,073,521.

Specification of Letters Patent. Patented Sept. 16, 1913.

Application filed May 28, 1912. Serial No. 700,152.

To all whom it may concern:

Be it known that I, JAMES H. REICHART, a citizen of the United States, and a resident of La Fayette, in the county of Tippecanoe and State of Indiana, have invented a new and Improved Illuminated Fountain, of which the following is a full, clear, and exact description.

My invention relates to illuminated fountains, and it has for its object to provide one which is cheap in construction, and which is light in weight and may be readily moved from place to place on the lawn, so that small householders may, at little expense, supply themselves with such fountains, which may be connected with a garden hose, and with the electric light wires in the house, and which will throw the beam of light upward and into the spray directed upward by the water nozzle.

Additional objects of the invention will appear in the following complete specification, in which the preferred form of the invention is disclosed.

In the drawings similar characters of reference indicate corresponding parts in both the views, in which—

Figure 1 is a sectional elevation of the invention; and Fig. 2 is a sectional view on the line 2—2 of Fig. 1.

By referring to the drawings it will be seen that a circular frame 5 is provided, having a circular conduit or spray member 6, with a top 7, having a concave portion 8, there being orifices 9 in the top member 7, at each side of this concave portion 8, and there also being orifices 10 in the top 7, in the said concave portion 8, these orifices 9 and 10 being disposed so that the water 40 which passes therethrough will be sprayed upward about the globe 11. This globe 11 has a neck 13 with its lower portion 12 flared outwardly, so that the screw members 14, which mesh in the threaded openings 15 45 in the upper portion 16 of the circular frame 5, may press against the said collar 13, and hold the globe 11 in position on the frame 5. Disposed in the circular frame 5 and secured thereto there is a shelf 18, to which the lamp 50 socket 17 is secured, this lamp socket 17 being provided to receive an incandescent electric lamp 19, which is disposed within the globe 11. Around the electric lamp 19 there is disposed an inverted cone-shaped reflector

20, which is secured to the lamp socket 17, 55 and which serves to throw the light from the electric lamp 19 upward, so that the light rays will strike against the spray of water which is directed upwardly through the orifices 9 and 10 in the circular conduit or spray member 6. There are openings 21 in the shelf 18, through which the electric wires 22 are disposed, which are connected with the lamp socket 17, for providing the electric lamp 19 with the necessary current. 65 In the outer side of the circular conduit or spray member 6, there is an opening 23, to which a collar 24 is secured, this collar 24 having an inner thread 25 for receiving a hose or pipe member for conveying water 70 to the said circular conduit or spray member 6.

It will be understood that when the wires 22 are connected with the electric current to light the lamp 19, and when water under 75 pressure is introduced in the circular conduit or spray member 6, through the collar 24, the water will be sprayed upwardly through the orifices 9 and 10, and about the globe 11, and that this water spray will be 80 illuminated by the electric lamp 19, the rays of which are thrown upward and outward to the water by the reflector 20.

Having thus described my invention, I claim as new and desire to secure by Letters 85 Patent—

In an illuminated fountain, a frame having an outer annular spray member at its bottom, serving as a base for resting on a lawn, the frame extending above the spray member and having a central lamp socket disposed above the horizontal plane at the top of the spray member, so that a lamp in the socket may throw its light laterally beyond the fountain, unobstructed by the frame, a reflector disposed around the lamp socket, and diverging upwardly therefrom, and a globe disposed over the lamp socket, and the reflector, and secured to the frame, within the spray member. 100

In testimony whereof I have signed my name to this specification in the presence of two subscribing witnesses.

JAMES HYTER REICHART.
